UNITED STATES PATENT OFFICE.

WILLIAM A. CAVETT, OF KIRKSVILLE, MISSOURI, ASSIGNOR OF ONE-HALF
TO HAYDEN A. PARSONS, OF LAPLATA, MISSOURI.

HAY-STACKER.

SPECIFICATION forming part of Letters Patent No. 674,495, dated May 21, 1901.

Application filed October 8, 1900. Serial No. 32,397. (No model.)

To all whom it may concern:

Be it known that I, WILLIAM A. CAVETT, a citizen of the United States, residing at Kirksville, in the county of Adair and State 5 of Missouri, have invented a new and useful Hay-Stacker, of which the following is a specification.

My invention is an improved hay-stacker; and it consists in the peculiar construction 10 and combination of devices hereinafter fully set forth, and pointed out in the claims.

In the accompanying drawings, Figure 1 is a perspective view of a hay-stacker embodying my improvements, showing the fork lowered. Fig. 2 is a detail view. Fig. 3 is a vertical longitudinal sectional view showing the fork raised to its highest position in full lines and in an intermediate position in dotted lines.

20 The ground or base frame 1 comprises the sills or runners 2 and the cross-bars 3 4 5. The cross-bar 3 is disposed at the end of the ground-frame which I will term the "inner" end, the cross-bar 4 is disposed near the center of the ground-frame, and the cross-bar 5 is disposed near the outer end thereof. A 25 pair of standards 6 rise from the cross-bar 3, and a differential pulley 7 has its bearings in the said standards. Said differential pulley 30 has the larger section 8 and the smaller section 9. A direction sheave or pulley 10 is supported on the cross-bar 3, and an operating-rope 11 is attached to the larger pulley or section 8 and is adapted to be coiled thereon 35 and to be uncoiled therefrom, and said operating-rope passes around one side of the direction-sheave 10, as shown. The standards 6 are braced by means of bars 12. Any other suitable means may be employed for bracing 40 said standards. A stop-frame 13 connects the cross-bars 4 5, and said stop-frame, which is of the form here shown, is provided with a cross-bar 14 at its upper side.

The fork-frame 15 has the extensible bars 45 16, forming the sides thereof, the inner ends of which are pivotally connected to the sills or runners of the ground-frame near the inner end of the latter, as at 17. The bars 16 comprise the inner pivotal sections *a*, and the 50 outer extensible sections *b*, which bear against

the sections *a*, are adapted to slide longitudinally thereon and are secured thereto by suitable keepers *c*. Stirrups *d* are pivoted to the inner sections *a*, and when the sections *b* are extended the said stirrups *d* may be caused 55 to engage the inner ends of the sections *b* to support the latter in their extended positions. A cross-bar 18 connects the inner sections *a* together, the ends of the said cross-bar bearing on the outer sections *b*. Braces 19 connect 60 the inner portions of said inner sections *a* to the central portion of cross-bar 18. At the free outer end of the fork-frame is the fork 20, which is of the construction shown. The short fork-fingers 21 are pivotally attached to 65 the head of the fork, as at 22, and are connected together by a cross-bar 23. Hook-rods 24 have their outer ends pivotally attached to two of the fingers 21, and the inner hooked ends of said rods 24 are attached to the sections *b* of the side bars of the fork-frame by 70 means of a series of adjusting-openings 25, with which said bars are provided. Thereby the fingers 21 may be disposed and secured at any desired angle with relation to the load- 75 carrying fingers of the fork.

A hoisting-frame 26 is pivotally connected at its lower end to the cross-bar 4 of the ground-frame, and said hoisting-frame is adapted to rock or oscillate. The same is 80 braced laterally by brace-rods 27, the lower ends of which are connected to eyebolts 28 on the ends of the cross-bar 4. When the hoisting-frame is in substantially a vertical position, as shown in Fig. 1, the same bears 85 against the cross-bar 14 of the stop-frame 13. In the upper end of the hoisting-frame is a differential pulley 29, which has a central section 30 and sections 31 on opposite sides thereof, the diameter of sections 31 being less than 90 the diameter of section 30. A hoisting-rope 32 is attached to the smaller section of differential pulley 7, is adapted to be coiled thereon and uncoiled therefrom, and said hoisting-rope is attached at its opposite end 95 to the larger section 30 of differential pulley 29 and is adapted to be coiled on and uncoiled from said section 30. Connecting-ropes 33 are attached to and adapted to be coiled upon and uncoiled from the smaller sections 31 of dif- 100

ferential pulley 29, and said ropes have hooks 34, which engage eyebolts on a bar 35, which is connected to the fork-head by rods 36. Chain-sections 37 of suitable length are attached to the said eyebolts and depend therefrom when the fork-frame is shortened, as shown in the drawings. When the said fork-frame is lengthened or extended, the hooks 34 of ropes 33 are detached from the eyebolts and attached to the free ends of the chains 37, which latter serve to increase the length of ropes 34 as is required by the extension of the length of the fork-frame.

A rocking frame 38, which I will term a "canting-frame," is of V shape and is pivotally attached to the stop-frame 13 at a point near the cross-bar 4, as at 39. When the said canting-frame is raised, it contacts with the outer side of the cross or stop bar 14. Said canting-frame is drawn downward normally by a spring 40. A rope 41 connects the free end of the canting-frame to the stop-bar 14, and said canting-frame carries a winch 42, to which is attached guy-ropes 43, which pass through guide-eyes 44, with which the canting-frame is provided, said guy-ropes being attached to the fork-frame near the free outer end thereof, as shown. The winch 42 serves to regulate the length of the guy-ropes, as will be understood.

The operation of my invention is as follows: When the fork has been loaded, a horse attached to the rope 11 in the usual manner is caused to draw outward on said rope, and thereby rotate the differential pulley 7 as the rope 11 uncoils from the larger section 8 thereof. The rotation of the differential pulley causes the sections 9 to slowly coil the rope 33 thereon and slowly uncoil the rope 32 from the larger section 30 of differential pulley 29 and by rotating said differential pulley cause the ropes 33 to be slowly coiled upon the smaller sections 31 of said pulley 29, and hence maximum leverage is exerted upon the fork-frame at the initial movement of the latter when the fork is started upward from the ground, which leverage is maintained until the rope 32 is entirely uncoiled from the larger section 30 of differential pulley 29, at which time the fork-frame has been elevated to an angle of about forty-five degrees from the ground. As the differential pulley 7 continues to be rotated by the rope 11 the rope 32, which continues to be coiled upon the smaller section 9 of differential pulley 7, draws the upper end of the hoisting-frame 26 toward the inner end of the ground-frame, thereby continuing to raise the fork, the frame 26 continuing to descend while the fork is being elevated, as will be understood. As the fork-frame nears the limit of its movement the guy-ropes 43 draw upward on the canting-frame against the tension of the spring 40, and the fork-frame continues to swing until the canting-frame is stopped by the bar 14 of stop-frame 13, at which point the fork by gravity

discharges its load onto the stack or rick which is in course of erection. The horse is then backed to slacken the rope 11, whereupon the canting-frame is drawn downward by the spring 40 and caused, through the guy-ropes 43, to cant the fork-frame rearward to overcome the dead-center, the weight of the fork-frame as it descends to its initial position causing the ropes 33 to rotate the differential pulley 29, the rope 32 to rotate the differential pulley 7, and the latter to reel up the rope 11 as said rope 11 is slackened.

Ordinarily while the stack is being erected the short fingers 21 of the fork-head will be disposed at such an angle with reference to the long fingers of the fork that the hay will be discharged by its own gravity from the fork when the latter reaches the upper limit of its movement. When the stack is nearly finished and it becomes necessary to top out the same, the short fingers 21 are so disposed with relation to the long fingers of the fork that they will not discharge the load by gravity from the fork, but will support the same when hoisted, so that a man stationed on the top of the stack can with a hay-fork remove the load from the stacker-fork and dispose the same appropriately on the cap of the stack while topping out and finishing the same.

Having thus described my invention, I claim—

1. In a hay-stacker, the combination of a ground-frame, a differential pulley thereon, a fork-frame, a hoisting-frame pivotally connected to the ground-frame, a differential pulley carried by the hoisting-frame, ropes connecting the fork-frame to the smaller sections of said latter differential pulley, a rope connecting the larger section thereof to the smaller section of the differential pulley on the ground-frame, and an operating-rope attached to the larger section of said latter differential pulley, substantially as described.

2. In a hay-stacker, the combination of a ground-frame, a differential pulley thereon, a fork-frame and hoisting-frame pivotally connected to the ground-frame, a differential pulley carried by the hoisting-frame, ropes connecting the fork-frame to the smaller sections of said latter differential pulley, a rope connecting the larger section thereof to the smaller section of the differential pulley on the ground-frame, an operating-rope attached to the larger section of said latter differential pulley, a canting-frame and guy-ropes connecting the latter to the fork-frame, substantially as described.

3. In a hay-stacker, the combination of a ground-frame, a differential pulley thereon, a fork-frame and hoisting-frame pivotally connected to the ground-frame, a differential pulley carried by the hoisting-frame, ropes connecting the fork-frame to the smaller sections of said latter differential pulley, a rope connecting the larger section thereof to the

smaller section of the differential pulley on the ground-frame, an operating-rope attached to the larger section of said latter differential pulley, a canting-frame and guy-ropes connecting the latter to the fork-frame, and a stop-frame to limit the movement of said canting and hoisting frames, substantially as described.

In testimony that I claim the foregoing as my own I have hereto affixed my signature in the presence of two witnesses.

WILLIAM A. CAVETT.
